Attorney.

UNITED STATES PATENT OFFICE.

JOSEPH WALTER, OF NEW YORK, N. Y., ASSIGNOR TO JOHN F. SIMONS,
FREDERICK M. SIMONS, AND EDWIN S. SIMONS, OF PHILADELPHIA,
PENNSYLVANIA.

DESIGN FOR A BACK FOR BRUSHES OR HAND-MIRRORS.

SPECIFICATION forming part of Design No. 22,704, dated August 15, 1893.

Application filed July 14, 1893. Serial No. 480,533. Term of patent 7 years.

To all whom it may concern:

Be it known that I, JOSEPH WALTER, of the city and county of New York and State of New York, have invented and produced a new Design for the Backs of Brushes or Hand-Mirrors, of which the following is a specification.

In the accompanying drawing the design is shown applied to the back of a brush or hand-mirror.

The design consists of the ornamental pattern arranged around the edge of the back composed of the alternate scrolls A and leaves B inclosing the plain or unornamented central portion C.

In dotted lines is shown a handle D such as may be used with the back of the brush or hand-mirror. This handle may be omitted if desired.

What I claim as new is—

The design for the back of a brush or hand-mirror substantially as described and as shown in the accompanying drawing.

In testimony of which invention I have hereunto set my hand.

JOSEPH WALTER.
